PUMP

Albert H. Winkler, South Bend, Ind., assignor to
Bendix Aviation Corporation, South Bend, Ind.,
a corporation of Delaware

Application November 30, 1944, Serial No. 565,933

8 Claims. (Cl. 103—227)

1

This invention relates generally to fluid pumps and has particular reference to positive displacement pumps. This application has subject matter in common with applicant's co-pending application Serial No. 500,893, filed September 2, 1943, the present invention being an improvement over the type of pump shown in Figures 5, 6 and 7 of said copending application.

While the invention in its broader aspects may be incorporated in pumps of various types and for various purposes it is shown and described herein incorporated in pumps of the positive pressure type for supplying fuel to charge forming devices or the like. In pumps of this character considerable difficulty has been encountered in effecting filling or priming of the pump chamber or chambers when the pump is started empty and it is therefore an important object of the present invention to provide a pump wherein rapid filling of the pump chamber or chambers may be automatically effected when the pump is started empty.

Another object of the invention is to provide a device of this character wherein the means mentioned in the next preceding paragraph will have no adverse effect on the efficiency and effectiveness of the pump under normal operating conditions.

Still another object of the invention is to provide a device of this character that is simple in construction and reliable in operation.

The characteristics and advantages of the invention are further sufficiently referred to in connection with the following detailed description of the accompanying drawings which represent a preferred embodiment of the invention. After considering this example, skilled persons will understand that many variations may be made without departing from the principles disclosed, and I contemplate the employments of any structures, modifications or modes of operation that are properly within the scope of the appended claims.

In the drawings:

Figure 1 is a diagrammatic view of a pump embodying the present invention; and

Figure 2 is a section taken on line 2—2 of Figure 1.

Referring to the drawings there is disclosed, for the purpose of illustrating the present invention, a reciprocating type of pump which includes a body portion 10 having a cylinder 12 in which a piston or pumping chamber 14 is reciprocably disposed. The piston may be reciprocated by any suitable means, the means herein shown, by way of example, comprising a shaft 16 journaled in the body portion 10 of said shaft and having a portion 18 of reduced size eccentric relative to the axis of the shaft 16. The extension 18 is disposed in the cross bore of a block 20 slidable in a

bore 22 in the piston 14 and at right angles to the axis thereof.

Fuel is supplied to the pump by fuel supply conduit 24 from a suitable source of fuel, said conduit being connected with a fuel inlet 26 of the pump, the fuel passing into the interior of the cylinder by way of a port 28 of such size and so located as to be in constant communication with an opening 30 into the cross bore 22 from which it passes into the chamber-like portions 31 at the opposite ends of the piston by way of ports 32. Both ends of the piston 14 are closed by walls 34. The pump is of the double-acting type and inasmuch as each side is constructed, and operates in the same manner, a description will be given herein of but the left hand side, as shown in the drawings. The wall or head of the piston 34 is provided with fuel passages 36 and the flow of fuel from the interior of the piston through said passages 36 into a chamber 38 is controlled by an inlet check valve 40 which comprises a rigid plate member 42, preferably of metal, attached to a valve stem 44 which extends into the piston and is substantially coaxial therewith. The plate member 42 carries a sealing gasket 46 (of neoprene or other suitable material) having a peripherally turned portion 47 adapted to engage the outer surface of the piston wall or head 34 encompassing the area thereof containing the ports 36. A conical spring 48 is secured to the valve stem 44 adjacent the free end thereof and reacts between the point whereat it is secured to said stem and the interior surface of the piston wall or head 34 thereby normally maintaining the valve in the closed position and preventing flow of fuel into chamber 38. An outlet check valve, generally indicated at 50, is provided and comprises a cup-shaped member 51 which is of rigid material, preferably metal. The member 51 has an outwardly extending flange 52 about the open end thereof which carries a gasket 54 of resilient material such as neoprene or the like. The outlet valve is of larger diameter than the piston and is adapted to engage a valve seat 56 formed about the open end of the cylinder 12. The valve 50 is secured to a flexible diaphragm 58 by means of a rivet 59, there being a reinforcing plate 60 secured by said rivet on the side of the diaphragm opposite the valve 50. It is to be noted that the marginal edge portion of the plate 60 is turned laterally away from the diaphragm to protect the latter from being cut or otherwise injured by the edge of said plate. The diaphragm is marginally secured between the end of the body member 10 and a cap 64 thereby forming an expansion chamber 66 which may be considered as extending between the valve seat 56 and the diaphragm 58 and posterior to the chamber 38. The cap 64 is cup-shaped to provide a spring chamber 68

in which is disposed a calibrated spring 70 adapted to react between the outer end or bottom wall of said cup and the plate 60 for urging the valve 50 closed. If desired the chamber 68 may be in communication with the atmosphere by means of passages 72 and 74. Alternatively the chamber 68 may be connected with an air scoop, supercharger or the like in which case the passage 74 is suitably connected therewith by means of a conduit 76. The purpose of such an arrangement is to properly balance the valve 50 at all times and therefore the relative fuel pressure is unaffected by changes in pressure occurring at the inlet opening of the carburetor being supplied with fuel by the pump.

In the arrangement herein disclosed the closed end portion of the valve 50 is so positioned and the stroke of the piston is of such length that the head 78 of the valve stem 44 of the inlet valve will engage the head 80 of rivet 59 as the piston approaches the outer limit of its stroke and when said piston has reached said outer limit the valve 50 will be slightly unseated. The pump is also provided with a fuel outlet 82 connected with the expansion chamber 66 by a passage 84, said outlet 82 being connected with a discharge conduit 86 which leads to the carburetor or any other device to be supplied with fuel.

Operation

The pump is operable independently of the direction of rotation of the drive shaft 16, it being of the double-acting, positive displacement type. Upon rotation of the shaft 16 the piston 14 is reciprocated in the cylinder 12 and, assuming that the pump is full of fuel, said fuel during the intake stroke of the piston is drawn into the inlet 24 and passes through the port 28 and passage 30 into the bore 22, thence into the chamber portions 31 adjacent the ends of the piston. From the chambers 31 the fuel passes through the openings 36 in the cylinder head 34 and into the chamber 38, it being noted that the outlet check valve 50 is closed during the intake stroke, and the inlet check valve 40 opens to permit the passage of fuel therewith. When the piston reaches the end of its intake stroke the inlet valve 40 is closed by the spring 48 and as the piston moves through its discharge stroke the pressure of said piston transmitted through the fuel in chamber 38 forces the outlet check valve 50 open, discharging said fuel into the chamber 66 and thence through passage 84, outlet 82 and discharge conduit 86. The device will operate as above described as long as the outlet is unrestricted. Under such operating conditions the diaphragm 58 will be forced outwardly a very limited extent against the resistance of spring 70. Should the outlet be partially restricted so that there is but a limited discharge of fuel the pressure developed in chambers 38 and 66 force the diaphragm 58 further to the left during the discharge stroke of the piston, the outward movement of the diaphragm effecting an enlargement of chamber 66 sufficient to take care of the difference in normal decrease in the volume of chamber 38 and the quantity of fuel discharge per stroke of the piston. Inasmuch as the outlet valve is controlled by the movable wall or diaphragm 58 the quantity of fuel drawn into the pump by the intake stroke of the piston will depend on the quantity of fuel in chambers 38 and 66. For example, should the outlet of the pump be restricted so that but one half of the maximum capacity thereof be discharged the remaining half of the fuel will re-

main in chambers 38 and 66 and no additional fuel will be drawn into the pump cylinder until the piston has travelled through the initial half of its intake stroke during which the excess fuel in chambers 38 and 66 will be returned to the cylinder under the force of spring 70. When this excess fuel has been returned to said cylinder the diaphragm has reached a position whereat the valve 50 is closed. Thereafter said valve provides an inflexible end wall for the cylinder and further movement of the piston on its intake stroke will draw more fuel into the pump. Should the flow from the outlet 82 be entirely cut off the diaphragm 58 would merely oscillate back and forth so as to maintain the volume trapped in chambers 38 and 66 constant notwithstanding the reciprocating action of the piston.

It is to be noted that the outlet check valve 50 is anterior to the expansion chamber 66 and that the position of the diaphragm controls the position of said check valve 50, the position of said diaphragm being, of course, determined by the quantity or volume of fuel discharged through the chamber 66.

It is to be further noted that certain difficulties may be encountered in devices of this character when a diaphragm is used as one wall of the expansion chamber and the fuel is drawn from a source by the pump suction. These difficulties arise from the tendency of portions of the diaphragm between the centrally reinforced portion and marginally clamped portion to oscillate back and forth and prevent the building up of pressure for the discharge of fuel from the pump, and the intake of the fuel during the intake stroke of the piston. However, the foregoing difficulty is overcome in the present invention by providing the large valve 50 which forms an inflexible end wall for the chamber 38 and insures the drawing of fuel into said chamber during the intake stroke of the piston. Otherwise during said intake stroke of the piston the above mentioned flexible portion of the diaphragm would merely be drawn toward the retreating piston and prevent establishment of the necessary pressure differential for drawing more fuel into the pump and during the discharge stroke said portions of the diaphragm will be forced outwardly and there would be no discharge of fuel.

Priming

Should the pump be started dry the chambers 38 and 66 would be filled with air as well as the interior of the piston and the conduit leading from the fuel supply source to the pump. Due to the compressibility of the air, considerable difficulty would be encountered in clearing the above mentioned parts of air. In order to overcome this difficulty the parts of the present invention are so constructed and arranged that, as above pointed out, when the piston approaches the end of its discharge stroke the head 78 of the valve stem 44 contacts the head 80 of the rivet 59 and positively forces open the valve 50 a limited amount thus permitting the air compressed in chamber 38 to escape into the chamber 66 and thence through the passage 84, outlet 82 and conduit 86. With this arrangement the air may be rapidly cleared from the parts above mentioned and fuel drawn into and discharged by the pump. It is to be further noted that it has been found that this arrangement has no material adverse effect on the efficiency of the pump under normal operating conditions.

It is thought that the invention and many of

its attendant advantages will be understood from the foregoing description and though said invention has been illustrated and described in connection with but a single embodiment it will be apparent that various changes may be made in the form, construction and arrangement of the parts without departing from the spirit and scope of the invention or sacrificing all of its material advantages, the form hereinabove described being merely a preferred embodiment.

I claim:

1. In a reciprocating pump: a cylinder having an open end; a reciprocable pumping member mounted in the cylinder and having its head adjacent the open end of said cylinder; a flexible diaphragm forming one wall of an expansible chamber at the open end of the cylinder; a substantially inflexible outlet valve carried by the diaphragm and adapted to close the open end of the cylinder and providing a second chamber between said valve and the head of the reciprocable member; and a valve controlled inlet passage communicating with the second chamber; said outlet valve being adapted to be mechanically engaged by the reciprocable member as the latter approaches the end of its discharge stroke and to be at least slightly unseated thereby when said member reaches the end of its discharge stroke.

2. In a reciprocating pump: a cylinder having an open end; a piston in said cylinder, said piston having a head; an inlet passage in said head; an inlet valve carried by the piston and controlling said passage; a flexible diaphragm forming one wall of an expansible chamber adapted to communicate with the inlet passage; a substantially inflexible outlet valve carried by the diaphragm and adapted to close the open end of the cylinder and form one wall of a second chamber, said second chamber being between said expansible chamber and the head of the piston; said outlet valve being adapted to be engaged by a portion of the inlet valve as the piston approaches the end of its discharge stroke and to be unseated when the piston is at the end of its discharge stroke.

3. In a double-acting reciprocating fuel pump: a cylinder; a pumping member reciprocable in said cylinder; a generally cup-shaped outlet valve capping each end of the cylinders and forming chambers between said outlet valve and the respective ends of the pumping member; flexible diaphragms carrying the respective outlet valves and forming walls of expansible chambers; springs urging the diaphragms in a direction to close the outlet valves, said springs being of predetermined calibration; and valve controlled inlet passages for the pump; said pumping member being adapted to engage the respective outlet valves as said member approaches the end of respective discharge strokes and to effect at least a limited positive opening of said valves when said pumping member reaches the end of the respective discharge strokes.

4. In a reciprocating pump: a cylinder having an open end; a reciprocating pumping member mounted in the cylinder; a flexible diaphragm forming a wall of an expansible chamber adjacent the open end of the cylinder; a substantially rigid outlet valve mounted in said chamber and adapted to close the open end of the cylinder; spring means resiliently urging said outlet valve to its closed position; said valve being displaced by fluid pressure during each discharge stroke

of said pumping member; and a valve-controlled inlet passage for conducting fluid to be pumped to said expansible chamber.

5. In a reciprocating pump: a cylinder having an open end; a reciprocating pumping member mounted in the cylinder and having a head movable adjacent the open end of the cylinder; a flexible diaphragm providing a wall of an expansible chamber at the open end of the cylinder; 10 a substantially rigid outlet valve carried by said diaphragm and adapted to close the open end of the cylinder and providing a second chamber between the outlet valve and the head of the reciprocating member; a spring urging the outlet valve to closed position, the outlet valve being displaced by fluid pressure during each discharge stroke of said pumping member; and a valve-controlled fluid inlet passage communicating with said second chamber.
- 20 6. In a reciprocating pump: a cylinder having an open end; a reciprocating pumping member mounted in the cylinder; a flexible diaphragm forming a wall of an expansible chamber adjacent the open end of the cylinder; a substantially rigid outlet valve in said chamber connected to said diaphragm and adapted to close the open end of the cylinder; a spring urging said outlet valve to its closed position; said diaphragm being adapted to modify the effective force exerted on 25 said valve by said spring in response to a variable fluid pressure external of said expansible chamber; and a valve-controlled inlet passage for conducting fluid to be pumped to said expansible chamber.
- 30 7. In a reciprocating pump: a cylinder having an open end; a reciprocating pumping member mounted in the cylinder; a flexible diaphragm forming a wall of an expansible chamber adjacent the open end of the cylinder; a substantially rigid outlet valve mounted in said chamber operatively connected to said diaphragm and adapted to close the open end of the cylinder; a spring urging said outlet valve toward its closed position; means for subjecting the back side of said diaphragm to a source of variable fluid pressure for varying the effective force of the spring on said valve; and a valve-controlled inlet passage for conducting fluid to be pumped to said expansible chamber.
- 35 8. A pump comprising a pumping chamber, a reciprocable pumping member, inlet and outlet valves for said chamber, an expansible chamber communicating with said pumping chamber and having a spring loaded movable wall, means for subjecting the outlet side of said movable wall to a source of variable pressure for modifying the effective force of said spring tending to move said wall, and means actuated by the pumping member for positively opening the outlet valve 40 as the pumping member approaches the end of its pumping stroke.
